UNITED STATES PATENT OFFICE.

RALPH S. MAXWELL, OF DETROIT, MICHIGAN, ASSIGNOR OF ONE-HALF TO JULIA M. PARKER, OF PORTLAND, OREGON.

LOAD-BINDING DEVICE.

1,245,607.

Specification of Letters Patent.

Patented Nov. 6, 1917.

Application filed June 30, 1916, Serial No. 106,954. Renewed June 23, 1917. Serial No. 176,634.

To all whom it may concern:

Be it known that I, RALPH S. MAXWELL, a citizen of the United States, and a resident of the city of Detroit, county of Wayne, 5 State of Michigan, have invented a new and useful Improvement in Load-Binding Devices, of which the following is a specification.

This invention relates generally to load binding devices and has particular reference to lumber load-binding devices to be used 10 on auto trucks.

The main object of my invention is to provide a load-binding device adapted for installation on an auto truck, said device being normally in position to permit the loading of said truck, and including power driven means for placing the device in binding position on the load, said means being 20 connected with the propeller shaft of the truck and adapted for operation when the truck is in motion. A device of this character eliminates the lost time usually consumed by the ordinary hand operated load 25 binders, and greatly increases the efficiency of auto-truck hauling.

The details of my invention are fully shown in the accompanying drawings, in which:

30 Figure 1 is a transverse, vertical section through the body of an auto truck, showing my load-binding device installed thereon, and in normal position before operation;

Fig. 2 is a larger-scaled sectional detail 35 of the hydraulic jack and adjacent parts;

Fig. 3 is an enlarged fragmental horizontal section of the binding frame taken on the line 3—3 of Fig. 1; and

Fig. 4 is a side elevation, partly in section, of the parts shown in Fig. 3; this view is taken approximately on the line 4—4 of Fig. 3.

a, a, represent the longitudinal chassis beams of an auto truck, and b is the propeller shaft. Load carrying beams c are rigidly mounted transversely on the chassis beams, a, and are adapted to support the load d. Said beams are made with a longitudinal T slot guideway e, the web of which 45 is provided with slots f, g. Slide legs h are movably supported in the guideway e, the

outward movement of said legs being limited by a stop-bolt i, bearing in the slots f. Said legs h are further provided with slots j, located in the vertical plane of the 55 slots g. Rigidly mounted on the outer ends of the slide legs h are the upright channel-irons k, which form the side members of my binding device. The slide legs h and channel-irons k are normally held in their extreme outer positions, as shown in Fig. 1, 60 by the action of expansion coil-springs l, which bear on rigid guide pins m, and which springs are adapted to be compressed when the channel-irons k are moved inwardly toward the load. Each channel k is further provided with a longitudinal slot n, idler pin o, hole o' and brackets p.

The top frame member consists of a channel-iron q, the ends r of which are reduced 70 and provided with a centrally located slot s. The ends r project through the slots n of the channel-irons k, and permit the top frame member to move downwardly relative to the side frame members, at the same time permitting the side frame members to move laterally with respect to the top frame member. The rectangular frame thus formed by the members c, k and q may be adjusted so that the sides and top may be caused to bear 80 against the load d and bind the latter securely in place on the truck.

Mounted in the top frame member q is a casting t, to which are anchored the corresponding ends of chains u. Each chain extends outwardly along the top frame member q, over a roller v, down the side frame member, over the idler pin o, through the hole o', slot j, slot g, and thence around a winding drum w, which is rotatably mounted 90 on a shaft x, supported by brackets y beneath the floor of the truck. Each roller v is rotatably mounted in arms v' of a slidable bearing v² (see Figs. 3 and 4), said arms being also provided with lugs v³ which bear 95 against the web of the channel k. A tie plate v⁴ extends beneath the slot s, and an eye-bolt v⁵, extending through said slot, ties the plate v⁴ and bearing v² together. This construction provides a convenient bearing 100 for the roller v, and permits the latter to adjust itself to any adjustment of the frame.

A tension spring α is suspended from an eye-bolt in the upper bracket p of each channel-iron k , and has at its lower end a sheave α' . A cable α'' runs over said sheave and has 5 its ends secured to the eye-bolt v and an eye-bolt in the lower bracket p . This arrangement assists in returning the parts to their normal position.

The winding drum w is provided on its 10 end with a bevel gear 2. A stub shaft 5, mounted in bearings 6, 7, has fixed thereon a sprocket wheel 8, and a bevel gear 9, the latter meshing with and adapted to drive the gear 2 and thus the winding drum w .

15 Referring now to Fig. 2, an idler sprocket 10, mounted on a pivot 11, is connected to the sprocket 8 by a chain drive 12.

A hydraulic piston cylinder 13 is supported approximately in the position indicated by the broken lines in Fig. 1, and 20 14 is a piston head reciprocable within said cylinder. The piston rod 15 is connected at its outer end to the chain 12, and the movements of the piston in the cylinder will 25 transmit corresponding rotation of the winding drum w . A compression coil-spring 16 (see Fig. 2) tends to hold the piston in retracted position.

A force pump, diagrammatically represented by 17 in Fig. 1, is supported on a bracket 18 beneath the floor of the truck. The outlet of said pump is connected with the rear end of the cylinder 13 by a conduit 19, and the inlet of the pump is connected 35 with the fore end of the cylinder by a conduit 20. Said conduits 19, 20 are further connected by a by-pass conduit 21, in which is located a valve 22. The valve is provided with an operating arm 23, and a link 24 connects said arm with a control lever 25, the latter being located at a convenient point near the driver's seat. A loose driving belt 26 connects the pump pulley 27 with a drive pulley 28, the latter being fast on the propeller shaft b . Said belt normally slips, but when tightened will transmit a positive drive 40 from the shaft b to the pump. A belt tightener pulley 29 is pivoted on an arm 30, the latter being fixed on a rock shaft 31. 45 Said shaft is rocked by a control lever 32 located near the driver's seat.

The general operation of my device is as follows:

The load d is transferred to the body of 55 the truck in any well known way. The auto truck may then be placed in operative driving state, and while the truck is gaining speed the belt tightener pulley 29 is thrown against the belt 26 so as to cause the pump to 60 be operated and the piston rod 15 projected from the cylinder. The movement of this rod will cause the winding drum w to be rotated counter-clockwise, having reference to Fig. 1, and the chains u will be wound on

said drum so as to cause the side frame members k to be drawn inwardly and the top frame member g to be drawn downwardly until said frame members bind firmly against the top and sides of the load, so as to thereby securely hold the latter in place. 65 70

When the load is to be discharged from the truck, the operator will open the valve 22 by means of the control lever 25, thereby forming a bypass from the front to the rear side of the piston cylinder, and the action of 75 the springs will cause the parts to be returned to normal position.

I claim:

1. In combination with an auto truck, a load binding device comprising a frame 80 mounted transversely on the body of said truck, and means for moving the sides of said frame inwardly so as to cause them to bind on the load.

2. In combination with an auto truck, a 85 load binding device comprising a frame mounted transversely on the body of said truck, means for adjusting the sides of said frame so as to cause them to bind on the load, and means for returning the sides of 90 the frame to initial position.

3. In combination with an auto truck, a load binding device comprising a frame mounted transversely on the body of said truck, means for adjusting the sides of said 95 frame so as to cause them to bind on the load, and spring means for returning the sides of the frame to initial position.

4. In combination with an auto truck, a load binding device comprising an adjustable frame mounted transversely on the body 100 of said truck, and means for adjusting the sides of said frame so as to cause them to bind on the load, said means including a hydraulic jack. 105

5. In combination with an auto truck, a load binding device comprising an adjustable frame mounted transversely on the body of said truck, means for adjusting the sides of said frame so as to cause them to bind on 110 the load, said means including a hydraulic jack, and driving connections between said jack and the propeller shaft of the truck. 115

6. In combination with an auto truck, a load binding device comprising an adjustable frame mounted transversely on the body of said truck, means for adjusting the sides of said frame so as to cause them to bind on the load, said means including a hydraulic jack, and releasable driving connections between 120 125 said jack and the propeller shaft of the truck.

7. In combination with an auto truck, a load binding device comprising, a rectangular, adjustable frame mounted transversely on the body of said truck, means for adjusting the sides of said frame so as to cause them to bind on the load and means for returning the sides of the frame to initial posi-

tion, said means including a hydraulic jack, and driving connections between said jack and the propeller shaft of the truck.

8. In combination with an auto truck, a load binding device comprising a rectangular, adjustable frame mounted transversely on the body of said truck, means for adjusting the sides of said frame so as to cause

them to bind on the load, said means including a hydraulic jack, releasable driving connections between said jack and the propeller shaft of the truck, and spring means for returning the sides of the frame to initial position.

RALPH S. MAXWELL.
